UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

METAL VESTIBULE-CAR DIAPHRAGM.

1,256,057.

Specification of Letters Patent.

Patented Feb. 12, 1918.

Application filed April 24, 1916. Serial No. 93,185.

To all whom it may concern:

Be it known that I, HARRY H. SCHROYER, a citizen of the United States, and a resident of the city of Chicago, in the county of Cook and State of Illinois, have invented certain new and useful Improvements in Metal Vestibule-Car Diaphragms; and I do hereby declare that the following is a full, clear, and exact description of the same, reference being had to the accompanying drawings, and to the numerals of reference marked thereon, which form a part of this specification.

This invention relates to an improved type of metal vestibule car diaphragm wherein a novel and efficient construction is utilized to permit expanding movements of the diaphragm with reference to a car on which it is mounted to take place, and with the parts in all positions of adjustment acting efficiently to provide a weatherproof passage on the interior of the vestibule diaphragm.

It is an object therefore of this invention to provide a metal car diaphragm construction wherein the parts are adjustably associated with one another to permit expansion and contraction of the diaphragm as well as weaving movements thereof, due to relative movement taking place between coupled cars on which the diaphragms are mounted, and yet operating to provide a weatherproof passage between the cars at all times and in all positions of adjustment of the diaphragm members.

It is also an object of this invention to construct a metal car diaphragm construction comprising stationary and movable sections with the stationary sections constructed to receive the movable sections telescoping therewith and in sealing relation therewith, and with the movable members of the interfitting diaphragm sections adjustably associated with one another to permit weaving movements of the diaphragm sections to take place due to relative movements between the cars on which said diaphragms are mounted.

It is furthermore an object of this invention to provide a metal car diaphragm construction wherein a novel association of members comprising the stationary and movable sections of the diaphragm, is provided to permit ready expansion and contraction of the diaphragm sections with respect to

one another and to permit flexing thereof due to variations in movement between cars coupled to one another between and upon which the diaphragms are mounted.

It is finally an object of this invention to provide a simple, efficient metal diaphragm construction readily adapted for use on standard types of cars.

The invention (in a preferred form) is illustrated in the drawings and hereinafter more fully described.

In the drawings:

Figure 1 is a fragmentary side view with parts broken away and shown in section, of a pair of diaphragms connected one to another and mounted on the ends of cars coupled together.

Fig. 2 is a fragmentary detail section taken on line 2—2 of Figs. 1 and 6, with parts omitted and parts shown in elevation.

Fig. 3 is a fragmentary detail section taken on line 3—3 of Fig. 1.

Fig. 4 is a fragmentary detail section taken on line 4—4 of Fig. 3, with parts in elevation.

Fig. 5 is a fragmentary detail section taken on line 5—5 of Fig. 1, with parts omitted and parts shown in elevation.

Fig. 6 is a fragmentary top plan view of the diaphragm construction, with parts broken away and parts shown in section.

Fig. 7 is a modified form of construction illustrating another type of connection of the side wall members of the movable diaphragm section to the face plate of the diaphragm.

As shown in the drawings:

The reference numeral 1, indicates as a whole the end of a car, and movably mounted beneath the platform thereof (not shown) is a channel 2, forming the front member of a platform buffing mechanism of any usual and well known construction secured and supported on which is a vestibule diaphragm face plate 3. As clearly shown in Fig. 1, an auxiliary buffing mechanism for the upper end of the face plate 3, is also provided, comprising a horizontally rearwardly directed rod 4, securely attached upon the rear surface of the face plate 3, extending rearwardly and slidably through certain frame members of the car body, and having a compression spring 5, coiled thereabout, adapted to resist inward sliding movement of said

rod with similar movements of the face plate and vestibule diaphragm. Forming a part of the car construction at the upper end thereof is a gabled or acute angled horizontally extending stationary roof plate 6, the rear margin of which is turned upwardly, and riveted or brazed to a vertical frame plate 7, forming a part of the car body, and the forward margin of which is secured to and beneath a built-up end plate construction 8, disposed beneath and supporting the end portion of the curved roof of the car.

Secured in any suitable manner to the front surface of the vertical frame plate 7, and projecting outwardly therefrom in parallel relation to the gabled top or roof plate 6, and of less width than the plate 6, is another gabled plate 9, which is flanged downwardly at its side and forward margins and attached to a horizontal ceiling plate 10, of the vestibule of the car, affording a compartment through which the associated rod 4, and spring 5, extend.

Secured in upright position on each side of the end of the car body are large channels, having an inner wall 11, and an outer wall 12, with the forward or outer margins of said respective walls flanged outwardly as clearly shown in Fig. 3. Provided upon each side of the car body are upright I-beams 13, and the respective channel members 11-12, of the vestibule diaphragm are secured thereto by angle irons 14 and 15, respectively, riveted to the flanges of said I-beams and to the side walls 12, of the channel members.

The elements of the movable section of the diaphragm are connected upon the face plate 3, and for this purpose a rearwardly tapered gabled roof plate member 16, is flanged at its forward margin and riveted to the rear surface of said face plate, as clearly shown in Figs. 1, 2, and 6, and extends rearwardly beneath the gabled top plate 6, and over the gabled top wall of the compartment or abutment member 9. Near its side margins, guide or abutment members 17, of trapezoidal section, as shown in Fig. 2, are provided, each consisting of a plate bent longitudinally into trapezoidal form and riveted or brazed beneath the surface of the roof plate 16, near the side margins thereof, and spaced therefrom to afford a recess therebetween. Slidably inserted in the recess between the trapezoidal abutment members 17, and said roof plate 16, are flat trapezoidal shaped wing plates 18, which, at their forward ends are connected by means of a pivot 19, to the roof plate 16, and each provided with a downwardly extending flange, the rear end of which fits slidably within the channels 11-12, of the stationary diaphragm section, as clearly shown in Figs. 5 and 6. As shown in Fig.

5, the top horizontal margin of the outer wall 12, of the channels 11-12, merely extends upwardly to afford an abutment against which the downwardly turned flange of the wing plate 18, may contact, while the inner walls 11, have their upper margins flanged inwardly in horizontal position and rigidly secured in any suitable manner by riveting or brazing beneath the ceiling plate 10, of the vestibule of the car. 75

Also secured adjustably to the face plate 3, on the rear surface thereof, are the side walls of the movable section of the diaphragm each comprising resilient angled divergent walls 21 and 22, respectively, integrally connected in a rounded bead portion 23, and with the rear margins of said respective wall members provided with strips of sealing material 24, which, owing to the resiliency of the wall members 21 and 22, are thrust into sealing contact with the interior surfaces of the channel walls 11 and 12. The upper margins of the wall members 22, are turned horizontally inwardly and provided with sealing strips 20, which bear upwardly beneath the flat surfaces of the trapezoidal abutment members 17, of the roof plate 16.

For the purpose of attachment of said resilient side walls 21-22, to the face plate 3, a pair of plates 25 and 26, are bolted on the rear surface of the face plate with the margins thereof curved, as clearly shown in Fig. 3, to afford a cylindrical recess within which the rounded or beaded portion 23, of said divergent wall members 21 and 22, fits and is capable of movement therein. As clearly shown in Fig. 4, at certain points in the length of the beaded rounded portion 23, of said side wall members, the metal is cut away, also the rounded margins of plates 25 and 26, are cut away in alignment with the cut away portions of bead 23, and inserted in the aligned notches thus formed are blocks 27, which are brazed or rigidly secured to plates 25-26, and which serve to prevent longitudinal movement of the rounded portion 23, in the retaining plates therefor, or in other words prevent vertical movement of the side walls 21-22, of the movable diaphragm section with reference to the face plate 3. A modification of the connection of the side wall members 21-22, of the movable diaphragm section to the face plate 3, is shown in Fig. 7, wherein in place of the plates 25 and 26, plates 28 and 29, are provided bolted flat upon the rear surface of the face plate 3, and with their adjacent margins turned inwardly and curved to afford a cylindrical recess to receive the beaded or rounded portions 23, of the side wall members 21-22. 115

A sealing mechanism is provided for the roof plate 16, at the point at which the same slides inwardly within the car end beneath 130

the gable top plate 6, and for this purpose, as clearly shown in Figs. 1 and 5, a pair of angled plates 30 and 31, respectively, are secured in inclined position on the built-up end plate member 8, of the car projecting outwardly therefrom with their lower margins spaced from one another and having mounted therein a sealing strip 32, normally impelled downwardly into contact 10 with the top surface of the gabled roof plate 15, by springs 33.

The operation is as follows:

Due to the flexible connection between the face plate 3, and the side wall members 21—22, of the movable diaphragm section, a flexing or weaving movement between the same is readily permitted and furthermore, owing to the fact that no rigid connection exists between the gable roof plate 16, of the movable diaphragm section and the side walls 21—22, thereof, adjustments with respect thereto due to variations in movement of the diaphragm with respect to the car, are also readily permitted. The telescoping movements of the movable diaphragm section composed of the side walls 21—22, and roof plate member 16, are readily permitted, owing to the fact that the resilient side wall members 21—22, telescope within 20 the fixed upright channel members 11—12, of the stationary diaphragm section, and the roof plate member 16, moves beneath the gabled stationary top plate roof member 6, sliding beneath the sealing strip 32, provided at the upper end of the car.

A certain angular movement of the face plate 3, with respect to the elements of the movable diaphragm section is permitted, and when such movement takes place, of course the face plate has a hinged action on the cylindrical or beaded portions 23, of the side walls 21—22, but the gabled roof member 16, moves as a unit therewith, and owing to the fact that the side margins thereof are tapered inwardly, as shown clearly in Fig. 6, the same is capable of swinging laterally with respect to the elements of the stationary diaphragm section. A seal between the gabled roof plate member 16, of the movable diaphragm section and its side walls 21—22, is effected by the pivotally mounted wing plates 18, which engage in the recess provided therefor beneath the side margins of the roof plate 16, and are turned downwardly to overlap the upper edge of the side wall members 22. As a consequence, when the swinging movements of the roof plate member 16, take place as the vestibule face plate 3, is caused to assume an angled position, the wing plates maintain substantially the same relation with the side walls 21—22, and the roof plate 16, slides with reference thereto, the seal, however, being always maintained, and when the associated roof plate 16, and

wing plates 18, move inwardly with respect to the stationary diaphragm section, said wing plates 18, engage within the channel members 11—12, contacting the inner surface of the walls 12.

70

I am aware that various details of construction may be varied through a wide range without departing from the principles of this invention, and I therefore do not purpose limiting the patent granted 75 otherwise than necessitated by the prior art.

I claim as my invention:

1. In a metal car diaphragm construction of the class described, a face plate, resilient side walls adjustably connected thereto and supported thereby, channel members forming a part of a stationary diaphragm section adapted to receive said side wall members telescoped therewithin, a roof plate member rigidly connected to the face plate, 80 and means movably associated therewith and overlapping said side wall members and adapted to move therewith into interfitting relation with said stationary diaphragm channels during adjusting movements of the 85 diaphragm.

2. In a vestibule diaphragm construction of the class described comprising a stationary and a movable diaphragm section, a face plate, resilient integrally connected divergent side walls hingedly connected thereto, stationary channel members forming a part of the stationary diaphragm section adapted to receive said side wall members telescoping therewithin, sealing means interposed between said side walls of the movable diaphragm section and the channel members of the stationary diaphragm section, roof plate members secured upon the rear surface of said face plate, movably mounted means affording a sealed connection between the roof plate member and said side walls of the movable diaphragm section, and sealing means associated with the stationary section of the diaphragm to seal along the upper surface of 100 said roof plate to seal the connection between the roof plate and the stationary diaphragm section in all positions of adjustment thereof.

105

110

115

120

125

130

3. In a vestibule diaphragm construction of the class described, stationary and movable diaphragm sections, the stationary section comprising upright channel members, a gabled roof plate member, a ceiling plate rigidly connected to the upper end of the upright channels, and said movable diaphragm section comprising a face plate, side walls hingedly connected thereto extending in sealing relation into said upright channels, a gabled roof plate member extending beneath said gabled roof plate member of the stationary diaphragm, and pivotally mounted wing plates adjustable with said roof plate member of the movable diaphragm section and overlapping the side walls of the movable diaphragm section and telescoping

ing within the channel members to afford an adjustable connection and seal between the roof plate member and side walls of the movable diaphragm sections in all positions 5 of adjustment.

4. In a vestibule diaphragm construction of the class described, the combination of a movable and a stationary diaphragm section, the movable diaphragm section comprising 10 side walls and a roof plate member, a sliding sealing connection between the roof plate member and the side walls, said stationary diaphragm section comprising upright channel members adapted to receive 15 the side walls of the movable diaphragm section telescoping therein, a roof plate member to receive the roof plate member of the movable diaphragm section moved therebeneath, and sealing means associated with said stationary diaphragm section 20 adapted to seal on the upper surface of the roof plate member of the movable diaphragm section.

5. In a vestibule diaphragm construction 25 of the class described, the combination with a face plate, of a gabled roof plate secured thereto, divergent integrally connected resilient side wall members hingedly connected to the rear surface of said face plate, a 30 slidable plate connection between said roof plate and said side wall members, compartment means adapted to receive the side wall members telescoping therewithin and to receive said roof plate member telescoping 35 therein, and sealing means to seal along the upper surface of the roof plate member at the line of entrance thereof into said compartment means.

6. In a vestibule diaphragm construction 40 of the class described, the combination with a face plate, of side wall members hingedly connected thereto, a roof plate member rigidly connected thereto, pivoted wing plates on said roof plate member having a sliding 45 engagement therewith adapted to overlap said side walls beneath said roof plate, and means adapted to receive said associated roof plate, side walls and wing plates members interfitting therein in telescoping relation.

50 7. In a vestibule diaphragm of the class described, a stationary and a movable diaphragm section, said stationary section embracing channel side walls, said movable section embracing pivotally mounted resilient 55 side walls sprung within said channel side walls and slidably therein, and sealing means associated with said interfitting side walls to afford a seal therebetween.

8. In a metal diaphragm construction of 60 the class described, stationary compartment side walls, a face plate, side walls hingedly mounted on each side of the face plate and slidably interfitting said compartment side walls, said hingedly mounted side walls each 65 comprising divergent resilient members to

insure close sliding contact thereof with the interior of said compartment side walls, and means insuring a seal between said interfitting side walls.

9. In a diaphragm of the class described, 70 a channel member, a face plate, a member hinged to the face plate comprising oppositely springing plates adapted to be sprung into the channel member and contact the walls of the channel member. 75

10. In a metallic diaphragm, a stationary side wall member and a movable side wall member comprising oppositely springing elements adapted to contact the stationary side wall member and have sliding engagement 80 therewith.

11. In a metallic diaphragm, a stationary side wall member, a movable side wall member comprising oppositely springing elements adapted to contact the stationary side 85 wall member and have sliding engagement therewith, and a sealing member on each element.

12. A metallic diaphragm comprising a stationary side wall and a movable side wall 90 comprising spring arms both yieldingly bearing against the stationary side wall and having a telescoping movement therewith.

13. In a metallic diaphragm, a movable side wall comprising oppositely impelled 95 spring plates.

14. In a device of the class described, a face plate, connected side wall members pivoted thereto springing outwardly, and a sealing strip along the outer edge of each 100 member.

15. In a diaphragm, a stationary side wall, and a movable side wall comprising two spring impelled resilient plates contacting opposite faces of the stationary side wall. 105

16. In a diaphragm, a face plate, plates connected by a bead which springs the plates oppositely, and means engaging the bead and pivotally attaching the plates to the face plate. 110

17. In a diaphragm, a movable side wall comprising oppositely impelled plates.

18. In a diaphragm, a movable side wall comprising oppositely impelled plates, and a sealing member secured to one edge of 115 each plate.

19. A metallic diaphragm comprising a stationary side wall channel member, and a movable side wall member sprung into the channel member affording a plurality of 120 seals for the entire length of the side wall.

20. In a diaphragm, a movable wall member comprising a sheet of metal shaped to provide integral oppositely sprung walls.

21. In a diaphragm, channel side walls, a 125 face plate, an arched roof plate rigidly secured thereto, an abutment member secured to the under side of each end of the roof plate, side wall members secured to the face plate extending into the channels, a plate 130

pivoted to each end of the roof plate between the roof plate and abutment block having its outer edge turned downwardly into the channel member, a flange on the upper end of each of the outer side wall members directed inwardly to extend beneath the respective abutment blocks, and a sealing member between each flange and the abutment block forming a weather tight joint.

22. In a diaphragm, telescoping side wall members, a movable roof member, pocket members secured to the roof member forming pockets, a plate secured in each pocket having its outer edge directed downwardly, and means secured to part of the telescoping

members adapted to engage beneath said pocket members and forming a seal.

23. In a diaphragm, a roof member, blocks, one secured to each end thereof forming a pocket between the same and roof member, a plate secured in the pocket having a down-turned outer end, side wall sections, and angularly directed flanges integral therewith bearing against the bottom of the blocks.

In testimony whereof I have hereunto subscribed my name in the presence of two subscribing witnesses.

HARRY H. SCHROYER.
